WORK GUIDE FOR WOODWORKING
MACHINES AND THE LIKE

Cecil F. Crow, Klamath Falls, Oreg.

Application April 21, 1950, Serial No. 157,395

5 Claims. (Cl. 144—253)

1

This invention relates to woodworking machinery and has special reference to a lumber guide for such machinery.

In such machines as molding machines and circular saws, it is customary to provide the machine with a bed wherethrough a cutting tool projects. Usually a guide is positioned on the head in adjustable relation to the cutting tool. This guide is adjustable bodily toward and from the cutting tool so as to accommodate different widths of lumber used in the production of strips having one or more molded edges varying slightly in width, and in the cutting operation the guide should rest against one edge of the lumber and urge it into position against a straight edge. In such machines rolls are provided to draw the lumber forward after it is positioned against the straight edge. If a board reaches the rolls before the guide has directed it against the straight edge, it will not be properly edged along its full length, no edging being effected for some distance along its entering end. Such an unedged end has to be cut off before the lumber can be marketed and about two feet in the length of the board will be scrapped.

One important object of this invention is to provide an improved construction of lumber guide which will, after once being set, open and close on any width of lumber for which the guide has been set.

A further important object of this invention is to provide a novel form of spring guide for holding lumber firmly against the straight edge of the machine to which the guide is applied.

Another object of the present invention is to provide a novel form of lumber guide having a leaf spring against which the lumber engages, the spring being so mounted that it may swing bodily about a pivot point.

A still further object of the invention is to provide a novel form of lumber guide having a leaf spring guiding member anchored at one end and having its other end provided with means for reinforcing its spring action.

With the above and other objects in view, as will be presently apparent, the invention consists in general of certain novel details of construction and combinations of parts hereinafter fully described, illustrated in the accompanying drawings, and particularly claimed.

In the drawings, like characters of reference indicate like parts in the several views, and

Figure 1 is a perspective view of this invention as applied to a woodworking machine;

Figure 2 is a plan view, partly in horizontal

2

section, of the invention and a portion of the bed of the machine to which it is applied; and

Figure 3 is a section on the line 3—3 of Figure 2.

For the purpose of illustrating the application of this guide to a woodworking machine, there has been shown in the drawings a portion of such a machine having a bed 10 on which is mounted a straight edge member 11 leading to a feed roller device part of which is shown at 12. Also, a piece of lumber B is shown which is held pressed down on the bed 10 by suitable means such as is shown at 13. In the bed 10 is provided a transversely extending slot 14 for purposes presently to be understood.

The guide forming this invention includes a base plate 15 on one end portion of which rests a head 16. A pivot bolt 17 passes through the head 16 and base plate 15. The lower end of the bolt 17 passes through the slot 14 and is there secured by a nut 18. An elongated slot 19 extends vertically through the head and is provided at one end with a recess 20. Through the recess 20, the plate 15 and the slot 14 extends a bolt 21 having a nut 22 on its lower end. This bolt 21 fits closely in the plate 15. Thus, by means of the bolts 17 and 21, the plate 15 may be adjusted along the slot 14 while being held against rocking on the pivot bolt 17. In the slot 19 is held a coiled compression spring 23 one end of which seats against the bolt 21 while the other end seats against the end of the slot 19 remote from the recess 20. This spring thus urges the head 16 in a clockwise direction of Figure 2, the bolt 21 constituting a limit stop for this movement by seating in the inner end of the recess 20. A cover 19' is provided for said slot 19 and recess 20.

One end of a leaf spring 24 is secured fixedly to the side of the head 16 adjacent the straight edge 11 by means of bolts 25. This spring extends from the head to lie opposite the straight edge and adjacent the feed roller means 12. On the end of the base plate 15 adjacent the feed roller means there is fixed a spring housing 26. Slidably mounted in and extending from the spring housing 26 is a rod 27. The housing 26 has an open end 28 into which the rod 27 extends to pass axially through the housing. At the other end of the housing is a head 29 having a central opening 30 through which the reduced and threaded end 31 of the rod 27 extends. Within the open end of the housing 26 the rod 27 is provided with a shoulder 32 facing the head 29. A coiled compression spring 33 surrounds the

rod 27 within the housing 26 and seats at one end of the shoulder 33, its other end seating against the head 29. A nut 34 and lock nut 35 are screwed on the threaded end 31 at the portion projecting from the housing 26. The spring 33 urges the rod outwardly of the housing but the outward movement of the rod 27 is limited by the nut 34.

In use, the base plate is adjusted on the bed 10 in such position that lumber of a width averaging that for which the base plate is adjusted will engage the leaf spring between the head 16 and the position of rod 27. If the lumber be somewhat over width, the engagement will take place nearer the head 16 and rock that head against the action of spring 23. If, on the contrary, the lumber be somewhat under width, it will engage the leaf spring remote from its anchored end where it yields more readily to flexure by reason of greater leverage. This condition will be compensated by the spring 33.

What is claimed is:

1. In a lumber guide for woodworking machines, a base plate, a head mounted on said base plate, a pivot bolt connecting the head pivotally with the base plate, said head having a vertical slot therein one wall whereof is provided with a vertical recess, a bolt extending through said recess and engaging in said base plate, a coiled compression spring in said slot between said last mentioned bolt and the wall of the slot opposite said recess, and a leaf spring having one end anchored to said head and extending freely therefrom.

2. In a lumber guide for woodworking machines, a base plate, a head mounted on said base plate, a pivot bolt connecting the head pivotally with the base plate, said head having a vertical slot therein one wall whereof is provided with a vertical recess, a bolt extending through said recess and engaging in said base plate, a coiled compression spring in said slot between said last mentioned bolt and the wall of the slot opposite said recess, a leaf spring having one end anchored to said head and extending freely therefrom, and spring urged means carried on said base plate and engaging the free end portion of said leaf spring to reinforce its resistance to flexure.

3. In a lumber guide for woodworking machines, a base plate, a head mounted on said base plate, a pivot bolt connecting the head pivotally with the base plate, said head having a vertical slot therein one wall whereof is provided with a vertical recess, a bolt extending through said recess and engaging in said base plate, a coiled compression spring in said slot between

said last mentioned bolt and the wall of the slot opposite said recess, a leaf spring having one end anchored to said head and extending freely therefrom, a spring housing fixed on the base plate and extending transversely thereof, said housing being remote from said head substantially perpendicular to said leaf spring, a rod in said housing extending from the housing and engaging the adjacent face of the leaf spring, and a coiled compression spring in said housing surrounding the rod and urging it outwardly against said leaf spring to increase the resistance of the leaf spring against deflection.

4. In a lumber guide for woodworking machines, a base plate, a head mounted on said base plate, a pivot bolt connecting the head pivotally with the base plate, said head having a vertical slot therein, a bolt extending through said slot at one end thereof and engaging in said base plate, a coiled compression spring in said slot between said last named bolt and the opposite end wall of the slot, and a leaf spring having one end anchored to said head and extending freely therefrom.

5. In a lumber guide for woodworking machines, a base plate, a head mounted on said base plate, a pivot bolt connecting the head pivotally with the base plate, said head having a vertical slot therein, a bolt extending through said slot at one end thereof and engaging in said base plate, a coiled compression spring in said slot between said last named bolt and the opposite end wall of the slot, a leaf spring having one end anchored to said head and extending freely therefrom, and spring urged means carried on said base plate and engaging the free end portion of said leaf spring to reinforce its resistance to flexure.
